(57) **CLAIM**

The ornamental design for a display screen with a transitional graphical user interface, as shown and described.

DESCRIPTION

FIG. 1 is a face view of a first state of a display screen with a transitional graphical user interface.

FIG. 2 is a face view of a second state of the display screen with a transitional graphical user interface; and,

FIG. 3 is a face view of a third state of the display screen with a transitional graphical user interface.

The broken lines represent a display screen and form no part of the claimed design. The broken lines represent portions of the transitional graphical user interface and form no part of the claimed design.

1 Claim, 3 Drawing Sheets

FIG. 1

FIG. 2

FIG. 3
